Primary Examiner — Rhea Shields*Assistant Examiner* — Lorna M Georges(74) *Attorney, Agent, or Firm* — Nitin Kaushik(57) **CLAIM**

The ornamental design for a charger, as shown and described.

DESCRIPTION

FIG. 1 is a front perspective view of a charger, showing my new design;

FIG. 2 is a rear perspective view thereof;

FIG. 3 is a folded stereogram of its front;

FIG. 4 is a folded stereogram of its rear;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines in the drawings illustrate the portions of the charger, which form no part of the claimed design.

1 Claim, 10 Drawing Sheets(56)
